(57) **CLAIM**

The ornamental design of a drum pallet, as shown and described.

DESCRIPTION

FIG. 1 shows a perspective view of a drum pallet showing our new design;

FIG. 2 shows a top plan view thereof;

FIG. 3 shows a side cross-sectional view thereof taken at line 3-3 of FIG. 2;

FIG. 4 shows a side cross-sectional view thereof taken at line 4-4 of FIG. 2;

FIG. 5 shows a bottom plan view thereof; and,

FIG. 6 shows a perspective view thereof along with a grouping of drums shown in broken lines.

The broken lines in FIG. 6 are shown for environmental purposes and form no part of the claimed design.

1 Claim, 5 Drawing Sheets
